MOLDED PULP SOUP BOWL

Wendell H. Stickney, Springdale, and Richard F. Reifers,
Westport, Conn., assignors to Diamond Gardner Cor-
poration, New York, N.Y., a corporation of Delaware

Application July 31, 1959, Serial No. 57,017

Term of patent 14 years

(Cl. D44—15)

FIG. 1

FIG. 2

FIG. 3

FIG. 4

FIG. 5

Fig. 1 is a bottom plan view of our new design for a molded pulp soup bowl;

Fig. 2 is an end view thereof in elevation;

Fig. 3 is a top plan view thereof;

Fig. 4 is a vertical section taken along line 4-4 of Fig. 3 and looking in the direction of the arrows; and

Fig. 5 is an enlarged fragmentary view in perspective illustrating in detail a portion of the bottom.

We claim:

The ornamental design for a molded pulp soup bowl, as shown.
